CLAIM

The ornamental design for a clothes hanger, as shown and described.

DESCRIPTION

FIG. 1 is a top plan view of a clothes hanger in accordance with the present design;

FIG. 2 is a front view of the clothes hanger of FIG. 1, a rear view being a mirror image thereof;

FIG. 3 is a bottom plan view of the clothes hanger of FIG. 1;

FIG. 4 is a first end view of the clothes hanger of FIG. 1; and, FIG. 5 is a second end view of the clothes hanger of FIG. 1. The broken lines shown represent unclaimed subject matter only and form no part of the claimed design.
